UNITED STATES PATENT OFFICE.

LAWRENCE A. SUBERS, OF EAST CLEVELAND, OHIO.

LAMINATED, COHESIVE, INTERWOUND, BONDED FABRIC.

1,230,338.

Specification of Letters Patent. Patented June 19, 1917.

Application filed July 21, 1914. Serial No. 852,173.

To all whom it may concern:

Be it known that I, LAWRENCE A. SUBERS, a citizen of the United States, and resident of East Cleveland, in the county of Cuyahoga and State of Ohio, have invented certain new and useful Improvements in a Laminated, Cohesive, Interwound, Bonded Fabric, of which I hereby declare the following to be a full, clear, and exact description, such as will enable others skilled in the art to which it appertains to make and use the same.

The objects of the invention are to provide a fabric of the type described in Letters Patent granted to Lawrence A. Subers upon March 26, 1912, and bearing Number 1,021,014.

This fabric has been described in the aforesaid Letters Patent as a laminated, cohering, interwound fabric, constructed upon a cylindrical mandrel, from series of spirally wound fabric bands, which cross each other at predetermined angles.

In the previously described fabric, the bands which comprise the fabric portion thereof are first made in tubular form and afterward flattened and are constructed from series of fibrous elements or flexible members which are coated with a liquid adhesive such as rubber during the process of construction of the band.

In my prior Patent No. 1,187,564, a flattened band of the same type as the preceding is described, in which in addition to the liquid adhesive with which the fibrous elements are coated during the construction of the band, a continuous layer of solid vulcanizable adhesive is interposed between the fibrous elements.

In this manner the amount of adhesive incorporated in the body of the band is greatly increased, and the fibrous elements in the sides of the flattened band will adhere together more strongly when the additional amount of adhesive is thus introduced, and will not readily tear apart when the band is placed under tension or strain. Also when the bands are placed under a preliminary tension to control the amount of subsequent extensibility thereof, this increased amount of adhesion will prevent any tendency of the bands to resume the tubular form.

To a complete understanding of the fabric the construction of the fabric bands must be understood.

These fabric bands are constructed from a plurality of series of parallel spaced, interwound, cohering fibrous elements, one series crossing the other at a predetermined angle and coated with liquid adhesive. Between the series of fibrous elements is interposed a continuous layer (which may be bands) of solid, vulcanizable adhesive, which fills all openings between the fibrous elements and appears upon the surface in regularly positioned diamond shaped spaces.

From such bands the laminated, cohering, interwound fabric is constructed, and the exposed diamond shaped portions of the adhesive in the crossing bands cohere together, thus binding the elements of the fabric more closely together and incorporating in the fabric a greatly increased amount of solid adhesive, and producing a bonded fabric which is possessed of a high resiliency, strength, and durability, and thereby greatly increasing its efficiency for general use.

This fabric, although a laminated structure, possesses no place of cleavage after it has been vulcanized, but is bound together into a homogeneous, unitary mass. The invention is hereinafter further described, shown in the accompanying drawings, and specifically pointed out in the claims.

In the accompanying drawings, Figure 1 is an isometric view showing the manner of constructing the fabric from series of fabric bands; Fig. 2 is a plan view of a tube showing portions of each series of bands broken away; Fig. 3 is a plan view of one of the fabric bands showing the diamond shaped spaces formed by the solid adhesive in its surface; Fig. 4 is a transverse section of one of the fabric bands, enlarged, and showing a rubber layer interposed between the yarn elements thereof; Fig. 5 is a similar enlarged section showing an added central band of rubber or other adhesive inclosed between the sides of the flattened band; Fig. 6 is a transverse section (enlarged) through line 6—6 Fig. 2, showing the layers of solid adhesive incorporated in the several fabric bands; Fig. 7 is a similar section showing fabric bands having a central band of rubber incorporated therein in addition to the other layers of solid adhesive; Fig. 8 is a longitudinal section on line 8—8 Fig. 6.

In these drawings A, A, are fabric bands formed originally upon a mandrel by wind-

ing the fibrous elements B. B. spirally thereon.

The structure is specifically described in said Patent No. 1,187,564 and the type of band is described by applicant's previously issued Letters Patent No. 1,021,014.

The bands in the present fabric are constructed by winding first a series of spaced parallel fibrous elements spirally upon a mandrel at a predetermined angle, then, second, by winding upon the same at preferably the same angle and in the opposite direction a similar series of spaced yarn elements, thus providing diamond shaped openings O. O. between the elements of the two series. Upon these series is applied the rubber layer, or other solid adhesive material, which may be composed of a continuous band or bands D. D. and a third and fourth series of spaced parallel, fibrous elements are wound thereupon, which are parallel respectively to the first and second laid series. The tube thus formed is then compressed and the sides of the tubular layer of rubber will cohere together through the diamond shaped openings wherever they coincide in the band and the sides of the tubular structure will be bonded together so that they will not afterward separate under such strains as the fabric may be subjected to.

This manner of construction incorporates a large amount of solid adhesive material within the band, in addition to fluid adhesive, and when the fabric band is placed under preliminary tension as described in said Patent No. 1,187,564, to remove a certain amount of its extensibility, it will retain a certain proportion of its elongation.

By means of the fluid and solid adhesives introduced therein as the fabric band is constructed, the fibrous elements are practically placed out of frictional contact with each other, so that the resiliency and durability of the fabric are greatly increased, and thereby the efficiency of the fabric for general use.

This structure is shown in Figs. 3 and 6.

In Fig. 5 an additional central rubber band D' is shown to incorporate an increased amount of adhesive in the fabric band where it may be required.

The structure of the improved fabric is illustrated in Figs. 1, 2, 6, 7, and 8, and is constructed in the manner described in the previously mentioned patents.

As shown in Fig. 1, a series, 1 of parallel spaced, fabric bands are wound at a predetermined angle upon a mandrel, a second similar series 2 is wound in the opposite direction so as to cross the first series, a third series 3 is wound parallel to the first series and so positioned as to substantially cover the spaces between the bands of the first series, and a fourth series 4 is wound at an

angle to the third series, the bands being so positioned as to substantially cover the spaces between the bands of the second series.

The appearance of the fabric in cross section is shown in Figs. 6 and 7, and in longitudinal section in Fig. 8.

It will be obvious to the observer that the fabric bands are connected and held together by the rubber or other adhesive which is incorporated within them, and which appears in the diamond shaped surfaces into which the pressure when flattening the bands has deflected it.

The adhesives in the exterior diamond shaped spaces make contact with each other and cohere together when the fabric bands are interwound to form the fabric.

Further advantages are found in its complete incorporation and envelopment of the fibrous elements in the vulcanizable adhesive in that they are substantially isolated from each other, and hence tend to eliminate friction upon each other, and also to protect them from moisture.

The body of the fabric is practically impervious to percolation of fluid under pressure since it is so dense and so much adhesive is incorporated therein that it can be stretched if necessary without admitting the fluid between the fibers of the elements.

An important feature of this fabric is determined by its extreme adjustability and control of the action of the fabric incorporated in a tube comprising several layers, when subjected to internal pressure.

This adjustability is obtained, first by means of the predetermined extensibility of the component bands in each layer, obtained by setting them in solid adhesive, and afterward stretching them as described in the Patent No. 1,187,564 application previously mentioned; and second by the relative angle at which the bands are laid in the several layers of the fabric. By these means, a substantially definite control of the fabric is obtained as regards elongation and expansion, and also as regards torsional twist, which can be practically eliminated.

Having described the invention, what I claim as new and desire to secure by Letters Patent is:

1. In a laminated fabric, a series of spaced, parallel, cohering, interwound, laminated fabric bands, each band composed in turn of crossed series of spaced, parallel, cohering, interwound fibrous elements, between the several series of which a layer of solid adhesive material is interposed, and which is exposed upon the exterior sides thereof in spaced positions, the solid adhesive upon the exterior sides of adjoining bands cohering in said fabric and serving as a bond to unite said bands into a unitary structure.

2. In a laminated fabric, a series of spaced, parallel, cohering and interwound, laminated, fabric bands, each band composed of series of parallel, cohering, interwound flexible, fibrous elements, one spaced series of elements crossing another spaced series of elements at a predetermined angle, providing spaced diamond shaped openings interspersed throughout the bands, some of 10 said diamond shaped openings being positioned in the outer surface of each band, and a solid adhesive filling all said openings, the adhesive filling the said surface openings in one band cohering to the adhesive filling the surface openings in adjacent bands and serving as a bond to unite the bands into a unitary structure.
3. In a laminated fabric, a series of spaced, parallel, cohering, interwound, laminated fabric bands, each band composed in turn of cross series, of spaced, parallel, cohering interwound fabric elements, the elements in each individual band being arranged in layers, and crossing each other 20 at an angle, and a layer of solid adhesive material interposed between adjacent layers of fibrous elements, said adhesive layer separating and cushioning said fibrous elements at crossing points and being exposed along the exterior side of each band in spaced positions, the solid adhesive upon the exterior sides of adjoining bands cohering in said fabric and serving as a bond to unite said bands into a unitary structure.
4. As an article of manufacture, a laminated fabric comprising a series of laminated, spaced, interwound, fabric bands, each of said bands comprising spaced, parallel, flexible elements interwound in layers, 30 the elements in one layer crossing those of another, and in which bands fluid adhesive is incorporated to cause the fibrous elements in said bands to cohere, said bands having interspersed and surface openings therein, said openings filled with a solid adhesive 40 and said solid adhesive also forming a cushion of material thickness between said elements at their crossing points, the adhesive in the several contacting bands cohering to form a bond for the fabric.
5. As an article of manufacture a laminated fabric comprising a series of spaced, parallel, cohering, interwound, laminated fabric bands, each band composed of crossed series of spaced, parallel, cohering, interwound fibrous elements, between the several series of which a layer of solid adhesive material is interposed, and which is exposed upon the exterior sides thereof in spaced positions, said exposed portions of the adhesive material being of a thickness substantially equal to the thickness of the surface portions of fabric on each side thereof.
6. In a laminated fabric, a series of laminated, cohering, interwound bands, each band provided with exterior and interspersed openings containing solid adhesive of material thickness compared with the thickness of the fabric layers adjacent thereto, the adhesive in the exterior openings in adjoining bands cohering to unite 50 said bands into a unitary structure.

In testimony whereof, I hereunto set my hand this eighteenth day of July, 1914.

LAWRENCE A. SUBERS.

In presence of—

ERNEST MOSMAN,
ADAM MEYER.
